UNITED STATES PATENT OFFICE.

MATTHEW J. STEVENS, OF RUBY, MICHIGAN.

STOVE ATTACHMENT.

SPECIFICATION forming part of Letters Patent No. 736,649, dated August 18, 1903.

Application filed January 6, 1903. Serial No. 138,053. (No model.)

To all whom it may concern:

Be it known that I, MATTHEW J. STEVENS, a citizen of the United States, residing at Ruby, in the county of St. Clair and State of Michigan, have invented a new and useful Stove Attachment, of which the following is a specification.

This invention relates to heating-stoves, and has for its object the production of a device whereby the heat radiated from the stove may be utilized to a greater extent and more uniformly distributed, with the accompanying economy in the consumption of fuel; and the invention consists in certain novel features of construction, as hereinafter shown and described, and specified in the claims.

In the drawings illustrative of the invention, Figure 1 is a sectional elevation of the device applied. Fig. 2 is a similar view illustrating a modification in the construction.

The improved device consists of an external drum 10, open at the upper end and provided with spaced apertures 11 relatively near the open end and adapted to be connected into the smoke-discharge flue of a heating-stove, 12 as shown.

The drum 10 may be formed of any desired length, and as many of the apertures 11 may be employed as required and the apertures formed of any required size. The drum will be of sheet metal, as light as possible consistent with the strains to which it will be subjected, as the lighter the drum the more rapid the circulation and consequent increased efficiency. When employed in connection with the smoke-flue leading from the stove, the drum 10 will be provided with an intermediate transverse partition 14, having spaced perforations 15 preferably near the walls of the drum, the partition being located below the perforations 11. Within the outer drum 10 is an inner drum 16, preferably conical and supported upon the partition 14 outside the perforations 15, so that the perforations are within the inner drum 16. The lower section 17 of the smoke-flue leading from the stove 12 is conducted into the outer drum below the partition, and the upper section 18 of the flue leads from the inner drum 16, as shown in Fig. 1. By this arrangement the smoke and other products of the combustion which pass through the flues 17 18 are retarded by the

partition 14 and deflected laterally therein and caused to pass through the apertures 15 relatively close to the walls of the outer drum, 55 thereby radiating the heat more thoroughly through the outer drum 10, and consequently more thoroughly effecting the air therein and producing the requisite circulation.

In Fig. 2 another slight change in the structure is shown, consisting in extending the lower portion of the outer drum below the line of the inner drum, as at 19, and providing this depending portion with spaced perforations 20, this depending portion serving 65 to create an additional circulation of the air, as indicated by the arrows. The hot air radiating from the stove contiguous to the flue-section 17 as well as the heat radiated from the lower flue-section is thus utilized to increase the circulation. By this simple arrangement a very rapid free circulation is imparted to the air and the air highly heated at the same time, thus economizing in the use of the fuel as well as insuring a more 75 wholesome condition of the atmosphere within the rooms.

Having thus described the invention, what I claim, is—

1. A heating apparatus consisting of an external drum open at the upper end and provided with an intermediate transverse partition having spaced perforations, said external drum having spaced perforations between the open end thereof and the partition, an 85 inner drum supported above said partition, an inner drum supported below said partition, a smoke-flue leading into said inner drum below said partition, and a smoke-flue leading from said inner drum above said partition, substantially as described.

2. A heating apparatus consisting of an outer drum open at the upper end and having an intermediate transverse partition provided with spaced apertures, the outer drum 95 having spaced perforations respectively above and below said partition, an inner drum supported above said partition, an inner drum supported below said partition, a smoke-flue leading into the inner drum below said partition, and a smoke-flue leading from the inner drum above said partition, substantially 100 as described.

3. A heating apparatus consisting of an

outer drum open at its upper end and having its walls provided with transverse perforations, a partition intermediately disposed within said drum below the perforations 5 therein and having spaced apertures near the walls of the drum, a conical drum supported within said outer drum upon said partition, a smoke-flue leading into said outer drum below said partition, and a smoke-flue lead-

ing from said conical drum above said partition, substantially as described.

In testimony that I claim the foregoing as my own I have hereto affixed my signature in the presence of two witnesses.

MATTHEW J. STEVENS.
